DECANTING DEVICE

Arnold D. Way, Bronxville, N. Y., assignor to The Permutit Company, New York, N. Y., a corporation of Delaware

Application November 13, 1950, Serial No. 195,442

7 Claims. (Cl. 210—29)

1

This invention relates to a decanting device for decanting liquid from a tank at a controlled rate, all as more fully described and as claimed hereinafter.

Existing decanting devices, especially those used in feeding chemical solutions or suspensions for treatment of water and other liquids are not wholly satisfactory.

The objects of this invention are to provide an improved decanting device of simple construction in which the passages through which the liquid flows are not likely to become clogged, and which is adaptable to a tank having a relatively high height-diameter ratio.

The manner in which these and other objects are achieved is shown in the appended drawings in which:

Fig. 1 is an elevation, partly in section, along lines 1—1 of Figs. 2 and 3 of a decanting device according to my invention;

Fig. 2 is a plan view of the device of Fig. 1;

Fig. 3 is a plan view, partly in section, along lines 3—3 of Fig. 1; and

Figs. 4 and 5 are diagrammatic illustrations of modifications of the device shown in Figs. 1, 2 and 3.

In the several views like numerals refer to like parts.

Referring now to Figs. 1 to 3, a decanting device according to my invention is shown in a tank 10 having an outlet 11 fixed to the side 12 adjacent to the bottom 13 of the tank 10. The tank 10 is provided with a cover 15 which has a trap door 16 attached by hinges 17 and provided with a handle 18 to permit access to the interior of the tank 10 without having to remove the cover 15. The cover 15 has openings 19 and 20 the purpose of which will be described later.

Attached to the outlet pipe 11 within the tank 10 is a draw-off system comprising a swing joint 22 which by means of a pipe 23 is connected to a swing joint 24 which, in turn, is connected by a pipe 25 to a draw-off head 26 provided with an overflow weir 27.

On top of the cover 15 is mounted a motor 30 which has a shaft 31 driving a gear reducer 32. On the slow-turning shaft 33 of the gear reducer 32 are mounted a small drum 34 and a large drum 35 carrying a crank 36. On the cover 15 is furthermore mounted guide means in the form of an idler drum 37 supported in a bracket 38. A flat tension member or tape 40 is fastened to the draw-off head 26 at 41 and also fastened to and wound up on the large drum 35, passing vertically up through the opening 19. Another tension member or tape 42 is fastened to the swing joint 24 at 43, passes through the opening 20, over idler drum 37 and is then fastened to and wound up on the small drum 34.

2

In operation the tank 10 is filled to the level 46 with the liquid 45 to be decanted. At this time the parts occupy the positions shown in solid lines in Fig. 1. The motor 30 is now operated and rotates shaft 33 with drums 34 and 35 in a counter-clockwise direction as viewed in Fig. 1. This unwinds the tapes 40 and 42 and lowers the draw-off head 26 and swing joint 24, the latter being lowered at a slower rate of speed because of the smaller diameter of drum 34. As the draw-off head 26 drops the liquid 45 is being decanted over weir 27 and out through pipes 25, 23 and 11. The dotted lines indicate the position when the level has dropped to the line indicated at 47 and the tank 10 is nearly empty. To refill the tank the crank 36 is turned in a clockwise direction thereby winding tape 40 on drum 35 and tape 42 on drum 34 and restoring the parts to the position shown in solid lines. Thereupon the tank 10 may be refilled with liquid through trap door 16.

The tapes 40 and 42 are advantageously made of high tensile strength stainless steel approximately one-half to one inch wide and 0.004 inch thick. Such tape has ample strength to support the draw-off system for tanks up to ten feet in diameter yet is not subject to corrosion by most liquids that may be decanted and does not appreciably change the effective diameters of drums 34 and 35 when the tapes 42 and 40, respectively, are wound up on such drums in several layers. With this arrangement the draw-off head 26 is being lowered in what is for all practical purposes a straight vertical line and the rate at which such head is being lowered is practically constant provided the speed of rotation of motor 30 is constant.

In Figs. 1 to 3 the distance from swing joint 22 to swing joint 24 equals the distance from the swing joint 24 to the fastening 41 on draw-off head 26, and the diameter of drum 34 is half the diameter of drum 35. Such dimensioning, however, may be modified as indicated in Fig. 4. If A is the distance from swing joint 22 to swing joint 24, B the distance from swing joint 24 to fastening 41, D_1 the diameter of drum 34 and D_2 the diameter of drum 35 as indicated in Fig. 4 the following relationship should be maintained to obtain straight line and uniform lowering of the draw-off head 26:

$$\frac{D_1}{D_2} = \frac{A}{A+B}$$

In the foregoing equation, if A equals B then D_2 equals $2D_1$ which is the arrangement shown in Figs. 1 to 3. While there is no critical value with regard to the limits of the difference between A and B, I believe that for best results B should not be less than one-half as long as A nor more than twice as long as A.

Fig. 5 shows a modification in which a drum 50 is rotatably attached to the swing joint 24 and the tape 42, after passing over idler drum 37, is passed around drum 50 and then fastened to a fixed support 51. In this modification the length A must equal the length B and the drums 34 and 35 are made of equal diameter as indicated at 52. With this arrangement the swing joint 24 will be lowered at one-half the rate of speed at which draw-off head 26 is being lowered.

A decanting device according to my invention is distinguished by the relative simplicity of the mechanical parts submerged in the liquid to be decanted. At the same time the liquid flowing through pipes 25, 23 and 11 encounters a steady pitch towards the outlet which is particularly important to prevent clogging when the liquid is a suspension as, for instance, milk of lime. When decanting is desired at a uniform rate, the motor 30 is operated continuously at constant speed. When decanting is desired at a variable rate, the motor 30 is controlled to operate at variable speed or intermittently as is well-known to those skilled in the art.

While I have shown and described what I consider the best embodiment of my invention, modifications other than those shown herein may be made without departing from the spirit of my invention and reference is, therefore, made to the following claims for a definition of the scope of my invention.

What I claim is:

1. A decanting device having a tank for liquid to be decanted, an outlet pipe near the bottom of said tank, a draw-off system comprising a swing joint attached to said outlet pipe within said tank, a second swing joint, a pipe leading from said first named swing joint to said second swing joint, a draw-off head, and a pipe leading from said second swing joint to said draw-off head, and means for lowering said draw-off system comprising support means located vertically above said draw-off head, other support means located above said second swing joint, a motor, a speed reducer operated by said motor and having a slow moving shaft mounted on one of said support means, drum means on said shaft, guide means mounted on the other of said support means, a tape wound up on said drum means and extending to said draw-off head, and another tape wound up on said drum means and extending to said second swing joint, one of said tapes passing over said guide means, said draw-off system and said means for lowering said draw-off system being so constructed and arranged that said pipe leading from said first named swing joint to said second swing joint and said pipe leading from said second swing joint to said draw-off head have a steady pitch from said draw-off head to said first named swing joint.

2. A decanting device having a tank for liquid to be decanted, an outlet pipe near the bottom of said tank, a draw-off system comprising a swing joint attached to said outlet pipe within said tank, a second swing joint, a pipe leading from said first named swing joint to said second swing joint, a draw-off head, and a pipe leading from said second swing joint to said draw-off head, and means for lowering said draw-off system comprising support means located vertically above said draw-off head, other support means located above said second swing joint, a motor, a speed reducer operated by said motor and having a slow moving shaft mounted on one of said support means, two drums on said shaft, guide

means mounted on the other of said support means, a tape wound up on one of said drums and extending to said draw-off head, and another tape wound up on the other of said drums and extending to said second swing joint, one of said tapes passing over said guide means, said draw-off system and said means for lowering said draw-off system being so constructed and arranged that said pipe leading from said first named swing joint to said second swing joint and said pipe leading from said second swing joint to said draw-off head have a steady pitch from said draw-off head to said first named swing joint.

3. A decanting device having a tank for liquid to be decanted, an outlet pipe near the bottom of said tank, a draw-off system comprising a swing joint attached to said outlet pipe within said tank, a second swing joint, a pipe leading from said first named swing joint to said second swing joint, a draw-off head, and a pipe leading from said second swing joint to said draw-off head, and means for lowering said draw-off system comprising a motor, a speed reducer operated by said motor and having a slow moving shaft, two drums on said shaft, a tape wound up on one of said drums and extending to said draw-off head, and another tape wound up on the other of said drums and extending to said second swing joint, the ratio of the diameter of said other drum to the diameter of said one drum being equal to the ratio of the distance between said first named swing joint and said second swing joint to the sum of said distance plus the distance between said second swing joint and said draw-off head.

4. A decanting device having a tank for liquid to be decanted, an outlet pipe near the bottom of said tank, a draw-off system comprising a swing joint attached to said outlet pipe within said tank, a second swing joint, a pipe leading from said first named swing joint to said second swing joint, a draw-off head, and a pipe leading from said second swing joint to said draw-off head, the distance between said first named swing joint and said second swing joint being equal to the distance between said second swing joint and said draw-off head, and means for lowering said draw-off system comprising a motor, a speed reducer operated by said motor and having a slow moving shaft, two drums on said shaft, a tape wound up on one of said drums and extending to said draw-off head, and another tape wound up on the other of said drums and extending to said second swing joint, the diameter of said other drum being equal to half the diameter of said one drum.

5. A decanting device having a tank for liquid to be decanted, an outlet pipe near the bottom of said tank, a draw-off system comprising a swing joint attached to said outlet pipe within said tank, a second swing joint, a pipe leading from said first named swing joint to said second swing joint, a draw-off head, and a pipe leading from said second swing joint to said draw-off head, and means for lowering said draw-off system comprising a motor, a speed reducer operated by said motor and having a slow moving shaft located vertically above said draw-off head, two drums on said shaft, a tape wound up on one of said drums and extending to said draw-off head, an idler drum located above said second swing joint, and another tape wound up on the other of said drums and extending over said idler drum to said second swing joint, said draw-off system and said means for lowering said draw-off system being so constructed and arranged that said

pipe leading from said first named swing joint to said second swing joint and said pipe leading from said second swing joint to said draw-off head have a steady pitch from said draw-off head to said first named swing joint.

6. A decanting device having a tank for liquid to be decanted, an outlet pipe near the bottom of said tank, a draw-off system comprising a swing joint attached to said outlet pipe within said tank, a second swing joint, a pipe leading from said first named swing joint to said second swing joint, a draw-off head, and a pipe leading from said second swing joint to said draw-off head, the distance from said first named swing joint to said second named swing joint being 15 equal to the distance from said second named swing joint to said draw-off head, and means for lowering said draw-off head at a predetermined rate of speed and said second swing joint at half said rate of speed comprising a motor, 20 a speed reducer operated by said motor and having a slow moving shaft, drum means on said shaft, a tape wound up on said drum means and extending to said draw-off head, and another tape wound up on said drum means and extending to said second swing joint, said draw-off system and said means for lowering said draw-off

system being so constructed and arranged that said pipe leading from said first named swing joint to said second swing joint and said pipe leading from said second swing joint to said draw-off head have a steady pitch from said draw-off head to said first named swing joint.

5 10

7. In the device of claim 6, a drum rotatably attached to said second swing joint, and a fixed support, said other tape passing around said last named drum to said fixed support.
